3. Charge receipt advance	18
VI. Consecutive Numbering Device	19

This invention relates generally to sales registering and recording devices of the type commonly referred to as cash registers.

Although referred to as cash registers, it will be appreciated that in recent years these machines have been redesigned and reoriented to handle various commercial transactions, such as the extension of credit to customers, and the words "cash register" are not to be interpreted in any narrow sense as indicating that only cash transactions may be registered and recorded thereby.

It is an object of this invention to provide an improved control mechanism for a cash register capable of issuing a cash receipt, of itemizing and totaling a transaction on a multiple copy charge slip, and of validating a bill, invoice, or similar instrument.

As a cash transaction is entered in the improved register, each item is added into an item accumulator and printed on a cash receipt tape. The tape is single spaced so the next item to be added can be listed on the tape directly below the previous one. When the transaction is totaled, the amount is printed on the next printing line and the receipt is jump spaced to the tear-off point. Also, the heading for the next receipt is printed. This heading may include the store name, date, and receipt number. A receipt numbering device is also advanced one unit so each receipt is identified by its own number. During the entering of a cash transaction, there are two primary item accumulator operations, adding and totaling. A subtotal operation is also provided for the purpose of computing a sales tax where necessary.

For a charge transaction, a multiple copy charge slip is inserted in the printing unit. The top copy receives its impression through an inked ribbon. Succeeding copies are prepared by the use of carbon paper or other pressure sensitive means. Each item is added into the item ac-

2

cumulator and printed on the charge slip. The charge slip is single spaced so that the next item to be added can be listed on the slip directly below the previous one. During this operation, no movement of the cash receipt tape takes place and nothing is printed on the receipt tape. Finally, the total of the charge transaction is printed on the charge slip. The slip is released but not jump spaced. Since the charge slips are preprinted forms, containing a heading and identifying number, no heading is printed and the numbering device is not advanced. During a charge transaction, there are also two primary item accumulator operations, adding and totaling. Also, a subtotal operation is provided.

The item accumulator has two conditions or positions, i.e., (1) an "in mesh" position in which the add pinions (and subtract pinions if used) are "in mesh" with add sectors for entering item amounts into the accumulator and for removing total amounts therefrom, and (2) an "out of mesh" position in which the add pinions are rotated away from the add sectors.

Printing of item and total amounts on both cash and charge transactions, single and jump spacing of the cash receipt tape, single spacing of the charge slip, printing of the tape heading on the cash receipt, advancing of a cash receipt numbering device, and opening of the cash drawer, all occur at about midcycle or during the second half or the return stroke of the machine. From about midcycle to the end of the machine cycle, the item accumulator is in mesh during add and subtotal operations, and out of mesh during a total operation. This binary condition of the item accumulator has been found to be particularly useful for the control of the above mentioned functions.

By providing a two position control shaft, the two positions of which correspond to the in mesh and out of mesh positions of the item accumulator, a very simple control over cash register functions is provided.

During a charge transaction, the use of a manually operable two position charge—cash or validate lever in conjunction with the two position control shaft provides all the control necessary, including the automatic return of the validate lever to the "cash" position during the total operation of a charge transaction.

It is therefore an object of the present invention to provide in a cash register an improved, simplified, two position control device which serves selectively to control a number of machine operations.

Another object is to provide a cash register with extreme flexibility of operation in differently handling the cash and credit receipt entries by means of a simplified common control. This object is achieved in the preferred embodiment by controlling a multiplicity of operations, such as the printing of item and total amounts on both cash and charge transactions, single and multiple advancing of the cash receipt tape roll upon which the items are entered, single spacing of a charge slip, printing of the tape heading on the cash receipt tape roll, advancing of a cash receipt numbering device, and opening of the cash drawer by the normal cyclic positioning of the item accumulator frame. A two position charge—cash control or validate lever is utilized in conjunction with the position of the item accumulator frame to provide the necessary control distinctions on charge and cash transactions.

Another object is the provision in a cash register of a common means for printing both cash and credit receipt tickets with a minimum number of operations and maximum flexibility.

It is another object of the present invention to provide improved receipt advancing and printing mechanisms for a cash register.

It is another object to provide improved means for selecting various distribution accumulators by the selective operation of corresponding function control keys.

Another object of the present invention is to provide an improved platen drive means for a cash register.

Another object is to provide an improved control means for a consecutive numbering device.

Other objects and features of the invention will be apparent from the following description, taken in conjunction with the accompanying drawings, in which

FIG. 1 is a perspective view of a cash register incorporating the present invention;

FIG. 2 is a fragmentary sectional elevational view along the line 2—2 of FIG. 3, illustrating certain of the numeral keys and the distribution accumulator and side printer drive mechanisms controlled by the keys;

FIG. 3 is a top plan view of the front or distribution accumulators;

FIG. 4 is a bottom plan view of the front or distribution accumulators;

FIGS. 5 and 6 are elevational views of the distribution key mechanisms in a nonactuated position and in one actuated position, respectively;

FIGS. 7 and 8 are fragmentary elevational views along the lines 7—7 and 8—8 of FIG. 3, illustrating the front accumulator position control means;

FIG. 9 is an elevational view of the side printer and the validate lever mechanism;

FIG. 10 is a fragmentary elevational view of the validate lever control mechanism;

FIG. 11 is a fragmentary elevational view illustrating the amount printing mechanism;

FIG. 12 is a fragmentary elevational view illustrating the heading printing mechanism;

FIGS. 13 and 14 are, respectively, a fragmentary side and an end elevational view illustrating the cash drawer control mechanism;

FIG. 15 is a fragmentary left side elevational view of the cash and charge receipt advancing mechanism in its initial position prior to the beginning of a cycle of machine operation for a cash transaction;

FIG. 16 is a fragmentary elevational view of a portion of the receipt advancing mechanism in the position it assumes when the item accumulator is shifted to the "in mesh" position during the initial part of the return stroke of an add operation for a cash transaction;

FIG. 17 is a fragmentary right side elevational view of the receipt advancing mechanism in the position it assumes at the end of the forward stroke of a total operation with the validate lever in the "charge" position;

FIG. 18 is a fragmentary elevational view of a portion of the receipt advancing mechanism in the position it assumes when the item accumulator is shifted to the "out of mesh" position during the initial part of the return stroke of a total operation for a cash transaction;

FIGS. 19 and 20 are end and side elevational views of that portion of the receipt advancing mechanism actuated by the item accumulator control shaft;

FIG. 21 is a perspective view of the consecutive numbering device and its actuating mechanism; and

FIG. 22 is a graph showing the timing of certain machine operations in relation to a complete stroke of the main shaft.

I. GENERAL ORGANIZATION

Unless otherwise explained, the words "front," "rear," "right," and "left" will be used in their normal sense to refer to the cash register as it is seen in FIG. 1. The improved cash register 40 includes appropriate sets of depressible numeral keys 42 for each denominational order of the amount to be registered for each item of the various transactions, a visual indicator 44, an item register tape 46 visible through an opening 48 in the case 49, a total-subtotal select lever 50, and a motor start bar 52. A cash-charge control or validate lever 54 is provided together with a set 56 of keys for controlling or selecting certain types of machine operations for transactions such as credit balance, amounts received on account, tax,

amount paid out, account forward, amount tendered, and the like, and also for identifying the clerks from whom various items to be entered have been received, such as groceries, produce, meat, and the like.

5 A side printer mechanism 58 is provided for preparing both cash and charge receipts for customers, and a cash drawer 60 is provided in the lower portion of the cash register. The cash register 40 includes the usual item accumulator (not shown) which is the working accumulator for obtaining the total cost of items purchased for each cash and charge transaction. The cash register also includes distribution accumulators designated "Cash," "Charge," "Tax," and "Received on Account" for accumulating the daily totals of the amounts of each of these transactions. Each of these accumulators is provided with a respective key in the set 56.

10 The cash register 40 is illustrated herein as applied to a calculating machine mechanism of the type shown in United States Patent No. 2,550,581, issued April 24, 1951, to Thomas O. Mehan, suitably modified to be conveniently operated as a cash register, and said patent is hereby incorporated herein by reference as if it were set forth in its entirety.

1. Adding and total taking functions

25 Briefly, the calculating machine of the patent includes a pivotal accumulator frame carrying a group of adding pinions and a group of subtracting pinions which, during adding, subtracting, subtotal, and total operations, are movable with the frame into mesh with segmental gears selectively actuated by key controlled racks to accumulate the total of a complete transaction.

30 The machine is equipped with the usual operating mechanism including a main shaft, is either electric motor driven or hand operated, and is provided with the usual interlocks, controls, and control keys common to this type of machine, as illustrated and described in greater detail in United States Patent No. 2,411,050, issued November 12, 1946, to Thomas O. Mehan. Frequently, a secondary main shaft connected for rotation with the primary main shaft, controls many of the machine functions, and the words "main shaft" as used in the specification and claims may be either the primary or secondary main shaft, depending upon the particular machine construction.

35 The item accumulator of the cash register 40 is preferably the same as the accumulator mechanism of Patent No. 2,550,581, and the above mentioned two position control shaft, which is utilized greatly to simplify the machine controls, is connected to an accumulator mechanism as will be described in detail hereinafter. The accumulator frame has two extreme pivotal positions, and the control shaft therefore has two extreme angular positions.

2. Numeral key operation for item and distribution accumulators

45 The numeral keys 42 (FIG. 2) are mounted in the usual key support plates 70, and the lower ends 72 of the stems 74 of the keys for each denominational order act as stops to limit the movement of Vernier type actuators 76 which are coupled by crossover plates 77 and pins 78 to racks 80. These racks control the positioning of the adding and subtracting pinions of the working accumulator.

50 The actuators 76 are provided with racks 82 which control the entry of items into the distribution accumulators. Each actuator 76 is associated with one denominational order of numeral keys 42, and therefore each rack 82 will enter a corresponding denominational order of the items in each of the distribution accumulators.

55 Each rack 82 meshes with a segmental gear 86 which is fixed to a hub 90 rotatable upon a shaft 92. The hub 90 has an adding sector 88 freely pivoted thereon, this sector being normally urged counterclockwise relative to the segmental gear 86 by a tension spring 97, one end of which 60 is secured to the adding sector 88 and the other end of

which is secured to a projecting arm on a disc 89 which is likewise fixed to the associated hub 90.

The adding sector 88 is normally held from counter-clockwise (FIG. 2) movement under the influence of its associated spring 87 by the engagement of a hook shaped end 93 of a transfer pawl 94 with a lug 95 projecting side-wardly from the sector 88, the transfer pawl 94 being pivoted upon a fixed shaft 96 and having a forwardly projecting arm 97 engaged by a transfer latch 98. The latch 98 and the transfer pawl 94 are both biased toward each other by a tension spring 99 connected between them.

Each of the adding sectors 88 is provided with a segmental gear 100 which is adapted to mesh with accumulator adding pinions 101 of each distribution accumulator. The adding pinions are rotatably mounted on a shaft 105. Each of the pinions 101 is provided with the usual transfer cam (not shown) fixed thereto, these cams being adapted to cooperate with and engage cam projection 102 formed on the transfer pawl 94 as its pinion 101 rotates from "9" position to "0" position.

As best seen in FIGS. 3 and 4, the accumulator mechanism of FIG. 2 is duplicated for each denominational order of numeral keys. The two rack positions at the right (FIG. 3) are not utilized in the preferred embodiment since, as can be seen in FIG. 1, the two positions for numeral keys at the right are not utilized.

There are four distribution accumulators provided in the front end of the machine, and therefore each rack 82 and its associated segmental gear 86 and add sector 88 must be utilized selectively to register items in the proper distribution accumulator. Accordingly, there is a group of four add pinions 101 associated with each add sector, each one of the add pinions being provided for a respective distribution accumulator. The distribution accumulators are carried on a swinging frame 150 (FIGS. 3 and 4) and the intermediate accumulator frame plates 103 are secured to a pivotal shaft 104 for movement of the adding pinions 101 into mesh with the segmental gears 100. The shaft 104 is received in journals 106 and 108 for both pivotal and reciprocable movement.

3. Type wheels in side printer

As best seen in FIGS. 2 and 3, the racks 80 also control the positioning of respective type wheels 110 in the side printer 58. The racks include toothed portions 112 (FIG. 2) which mesh with pinions 114 rotatably mounted on a shaft 116. Gears 118 of larger diameter than pinion 114 are secured to hub portions of the pinions 114 for rotation with the pinions. The gears 118 in turn mesh with gears 120 which are welded to adjacent ends of respective ones of a plurality of concentric tubes 122 carried by a rod 123 for rotation relative to each other. The opposite ends of the tubes 122 include slots 124 which receive inwardly extending lugs 125 on the type wheels 110. Thus, each of the racks 80 selectively positions a corresponding type wheel 110 by way of its gear portion 112, pinion 114, gears 118 and 120, and tube 122.

II. DISTRIBUTION ACCUMULATORS

Reference is now directed to FIGS. 2, 3, 4, 7 and 8 in which are illustrated a reciprocable accumulator selection slide 152 and an accumulator extension 154 which is parallel to and spaced from the slide 152. As seen in FIGS. 2 and 4, the extension 154 is secured to and supported by a channel 155 by a screw 157 and a stud 159 and C-clip 161. The channel 155 snugly receives in mating slots the accumulator frame plates 103 to shift the accumulator assembly, including the add pinions 101, laterally with the extension 154 as will be described below for selective positioning of desired pinions in mesh with their corresponding segmental gears 100.

At one extreme end the extension 154 has a U-shaped slot 156 which receives a stud 158 carried by a pivot arm 160. The arm 160 is carried by a sleeve 163 freely pivotal on a shaft assembly 162 which is carried by upper

and lower brackets 164 and 166, which brackets are suitably secured to an end frame plate 168. The arm 160 is pivotally secured to an extension 170 on the selection slide 152 by means of an eccentric adjustment shoulder screw 172 and a nut 174. Thus, when the arm 160 pivots about its axis, the accumulator selection slide 152 and the accumulator extension 154 will be moved in opposite directions.

A drive link 176 is moved toward the front of the machine by the main shaft cam, not shown, at a predetermined time interval during the forward stroke of the machine. A spring 178 secured to the link and to a stud 180 on the end frame plate 168 biases the link toward the rear of the machine. The drive link is operatively connected to the shaft assembly 162 by a crank 182 which is fixed to the shaft assembly 162 and which is connected to the drive link by a stud 184. A second pivot arm 186 is secured to the shaft assembly 162 and is therefore rotated with the shaft assembly when the drive link 176 is moved in the direction of the arrows in FIGS. 3 and 4 by means including the main shaft during the forward stroke of each cycle of machine operation.

The link 176 rotates the bellcrank 182, the shaft assembly 162, and the pivot arm 186 in a counterclockwise direction (FIG. 4) about the axis of the shaft assembly when the link is moved in the direction of the arrows; and a strong spring 188, secured to the stud 159 on the accumulator extension 154 and received through an aperture 192 on the arm 186, shifts the extension toward the right (FIG. 4). A stud 194 on the arm 186 engages a shoulder 196 on the extension 154 when the drive link 176 is returned to its normal position by the spring 178 to return the arm 186 to the normal position as shown in FIGS. 3 and 4.

Adjustable screws 198 and 200 and cooperating nuts 202 and 204 are engaged by the ends of the shaft 104 to limit the lateral travel of the accumulator assembly. The position of the screw 200 determines the at rest return position of the swinging frame 150 and the screw 198 determines the maximum travel of the swinging frame.

When the arm 186 is rotated counterclockwise by the drive link 176, as described above, to move the accumulator extension 154 toward the right (FIG. 4), the pin 153 and the cooperating slot 156 cause the arm 160 to rotate counterclockwise to move the accumulator selection slide 152 toward the left. The drive connection between the drive link 176 and the accumulator extension 154 is resilient since it includes the spring 188. This resilient drive connection permits the accumulator selection slide 152 to be stopped in a position determined by a rotatable U-shaped flag 208 and shoulders 209 and 210 on the slide as will now appear.

1. Distribution accumulator selection

In a typical embodiment, the four distribution accumulators are provided for the entry of each item entered into the cash register for cash sale, charge, tax, and received on account. The entry of items for each of these functions is accompanied by the depression of respective keys 212, 214, 216, and 218 of FIGS. 5 and 6. These keys cooperate with a vernier slide 220 selectively to position the flag 208 in any one of four positions with respect to an upstanding lip 222 on the accumulator selection slide 152.

The slide 220 carries a pin 224 which is engageable with a shoulder 226 at the upper end of the flag 208, and a bias spring 228 urges the flag counterclockwise against the pin. Depression of the key 218 will not affect the position of the slide, and the lip 222 of the accumulator selection slide 152 will engage the flag 208 in the position shown in FIGS. 3 and 4. In this position, the slide 152 prevents movement of the extension 154 when the drive link 176 is moved forwardly during the forward stroke of the machine. This position is utilized for entry of information into one of the distribution accumulators.

The slide 220 includes upstanding wedge members 232, 234, and 236, which cooperate with projections 238, 240, and 242 on the keys 212, 214, and 216 to move the slide 220 to succeeding positions toward the left with respect to FIG. 5 upon depression of the respective keys 212, 214, and 216.

The flag 208 includes stepped shoulders 244 and 246 which are positioned in alignment with the upstanding lip 222 when the keys 212 and 214 respectively are depressed. When the shoulder 244 is in alignment with the lip 222, the accumulator selection slide will ride thereunder until the shoulder 209 engages the flag and this positions the swinging frame 150 for the entry of information into the distribution accumulator corresponding to the key 212. Similarly, when the shoulder 246 is in alignment with the upstanding lip 222, the selector slide 152 will move until the shoulder 210 engages the flag, which positions the swinging frame for the entry of information into the distribution accumulator corresponding to the key 214. When the key 216 is depressed, the flag 208 is rotated out of the path of the upstanding lip 222 and the swinging frame is permitted to move until the shaft 104 (FIG. 4) engages the screw 198, which positions the swinging frame for the entry of information into the distribution accumulator corresponding to the key 216.

2. Aligning the distribution accumulators in selected position

An aligner 250 (FIGS. 7 and 8) is utilized for more precise positioning of the distribution accumulator adding pinions 101 with the adding sectors 100. The aligner 250 has a lower knife edge 252 which is cooperable with slots 254 (FIG. 5) in the accumulator extension 154 for precise positioning of the adding pinions in each of the four positions of the accumulator extension. The timing of the movement of the aligner during the machine cycle is controlled by way of a second drive link 255, which is actuated by a main shaft cam (not shown) shortly after the link 176 positions the swinging frame 150.

As best seen in FIGS. 4 and 7, the drive link 255 is connected to a stud 257 on a crank arm 256 which has a hub 259 secured to a pivotal shaft 258 which extends through the distribution accumulator assembly. A second crank arm 256a having a hub 259a is secured to the other end of the shaft 258. The upper end of each crank arm has a U-shaped slot 260. The shaft 258 also carries the aligner 250 for pivotal movement into and out of the slots 254 in the accumulator extension. An actuator stud 262 is received in a U-shaped slot 263 in the aligner 250 and is secured to a crank arm 264 which is pivotally mounted on the shaft 92. A second crank arm 264a is secured to the left end of the shaft 92 (FIG. 4) and carries a stud (not shown) corresponding to stud 262 which is received through a slot in the crank arm 256a corresponding to slot 260 in crank arm 256. When the crank arm 256 is rotated clockwise with respect to FIG. 7 by the drive link 255, the crank arm rotates the shaft 258 clockwise. The aligner 250 and the crank arm 256a are rotated clockwise (FIG. 8) with the shaft 258 to rotate the crank arms 264 and 264a counterclockwise (FIG. 8) on the shaft 92.

3. Shifting distribution accumulators into engagement with amount entering gears

The adding pinion shaft 105 is received within slots 258 in the crank arms 264 and 264a, and when the arms are rotated counterclockwise as described above, the adding pinion shaft is moved in an arc generally upwardly and toward the left with respect to FIG. 8, until the selectively aligned adding pinion set of one distribution accumulator (FIG. 2) is moved into mesh with the segmental gears 100 on the adding sectors 88. It will be noted that the aligner 250 moves into the slots in the accumulator extension prior to the meshing engagement of the adding pinions with the adding segmental gears. 75

III. SIDE PRINTER AND CONTROLS

The side printer 58 and its various control mechanisms will now be described in detail. With respect to FIGS. 9 and 10, it will be seen that the side printer 58 includes upper and lower housings 280 and 282 between which is an open generally horizontal slot 284 through which cash receipt tape 286 from a roll 288 is received. An inked ribbon 283, movement of which is controlled by the usual supply and rewind mechanism 285, is provided.

At the forward end of the slot 284, the cash receipt tape is received between a tape advance roller 290 and a freely rotatable pressure roller 292. The tape supply roll is rotatable on a shaft 289, and a light tension mechanism 291 takes up slack in the tape.

In the event that a charge transaction is being made, a charge receipt (not shown) is placed in the slot 284 above the tape 286 and between the tape advance roller 290 and an upper freely rotatable pressure roller 294. The tape advance roller 290 is operable in either direction under the control of a tape advancing mechanism which will be described later. The upper and lower pressure rollers 294 and 292 are carried on a pivotal member 296 which is actuated to either of two angular positions under the control of the validate lever 54 to bring one of the two pressure rollers into tight frictional engagement with the cash or charge receipt and the tape advance roller 290.

1. Validate lever operation

30 In the cash position of the validate lever 54, as shown in FIG. 9, the roller 292 is in engagement with the roller 290. When the arm 54 is moved toward the rear to the charge position of FIG. 10, it pivots about the axis of its supporting stud 298 in a clockwise direction. The member 296 is also freely pivotal on the stud 298, and a spring 300 connected between a lower hooklike projection 301 on the member 296 and a stud 302 on the lower end of the lever 54, rotates the member 296 in a clockwise direction to bring the upper pressure roller 294 downwardly against the tape advance roller 290. A pair of slots 304 in the member 296 receive screws 306 therethrough which act as guides and limit stops for the movement of the member.

35 A manually operable lever 310 is provided for releasing the validate lever 54. The lever 310 is secured to a rocker arm 311 pivoted on a shaft 313. When the validate lever is moved from the cash position of FIG. 9 to the charge position shown in FIG. 10, the lever 54 moves a slide 312 toward the left (FIG. 10) by means of a stud 314 secured to the lever and a lost motion slot 316 in the slide through which the stud is received. The slide rotates a crank arm 40 318, secured to a shaft 320 in a counterclockwise direction (FIG. 10). The other end of the shaft 320 carries a latch 321 having an L-shaped recess 322 engageable with a roller 323 carried by the arm 311. A spring 324 secured to the arm 311 urges the roller 323 against the latch 321. 45 Counterclockwise rotation of the validate lever 54 to the charge position permits counterclockwise movement of the arm 311 by the spring 324, the roller 323 moving downwardly into the recess 322 to maintain the latch in the charge position as shown in FIG. 10.

50 Manual movement of the lever 310 upwardly rotates the arm 311 clockwise to release the latch 321 so that the validate lever is returned to the cash position, as will appear below. As will be described later, the shaft 320 also conditions the tape advance mechanism for proper operation thereof for a charge transaction, and the latch mechanism will be released automatically subsequent to a total operation on a charge transaction to return the validate lever 54 to the cash position.

55 The return of the validate lever from the charge to the cash position is begun by the spring 300. During the first portion of the counterclockwise rotation of lever 54, roller 344 carried by the validate lever rolls on a dwell portion 336 of a rocker arm 340. During this time rocker arm 340 does not move and roll 344 carried thereby is not in

contact with arm 296. After the lever 54 has rotated counterclockwise, a small amount, roller 344 starts down cam surface 338. This permits spring 342 to rock arm 340 clockwise and assist the spring 300. As the arm 340 rotates, roller 346 contacts and rotates arm 296 in a counterclockwise direction to its forward or cash position. When in the cash position, the roller 344 clears the arm 340 and the roll 346 contacts the arm 296. When in the charge position, the roll 346 clears arm 296 and roller 344 is in contact with the rocker arm 340.

Return of the validate lever 54 to its cash position returns the slide 312, the crank arm 318, the shaft 320, and the latch 321 to their cash positions, the roller 323 being urged by the spring 324 against the uppermost surface of the latch 321 to the left of recess 322.

At the end of each charge transaction, the validate lever 54 is automatically returned to the cash position. This is achieved by a mechanism operable during the return stroke of a total cycle on a charge transaction. This mechanism includes a lever 350 (FIG. 10) pivotally carried by a stud 352 on the rocker arm 311. When the validate lever is moved to the charge position as described above, the counterclockwise rotation of the rocker arm 311 moves the lever 350 toward the right, which positions its projection or lug 356 in the path of a roller 355 carried by a crank arm 357 secured to the main shaft 359. The lower end of the lever 350 carries a stud 353 pivotally connected to a slide 354. As will appear later during the detailed description of FIG. 12, the slide 354 is moved to a position forward of that shown in FIG. 10 when the item accumulator is in its in mesh position, and is returned to the position of FIG. 10 when the item accumulator is in its out of mesh position.

With reference to FIG. 22, it will be seen that during the major portion of the return stroke of add and subtract operations, the item accumulator is in the in mesh position, and that during the major portion of the return stroke of a total operation the item accumulator is in the out of mesh position. It will be seen, during the description of FIG. 12, that the slide 354 is maintained in the position of FIG. 10 when the item accumulator is in the out of mesh position and is moved to a position forwardly of the position shown in FIG. 10 when the item accumulator is in the in mesh position. This forward movement of the slide 354 rotates the lever 350 about the axis of the stud 352 until its projection 356 moves out of the path of the roller 355, whereby the validate lever mechanism is not released during the add, subtract, and subtotal operations.

As seen in FIG. 22, the item accumulator is in the out of mesh position during the forward stroke of add and subtract cycles and that the projection 356 on the lever 350 is in the path of the roller 355. During the forward stroke of the machine the main shaft 359 rotates the crank arm 357 and the roller 355 in a counterclockwise direction (FIG. 10) and midway during the forward stroke the roller 355 engages the projection 356 to rotate the lever 350 in a clockwise direction about the stud 352. As will be described with respect to FIG. 12, the slide 354 has a biased lost motion connection permitting this clockwise rotation of the lever 350 and as soon as the roller 355 passes the projection 356, this bias connection permits the return of the lever 350 to the position shown in FIG. 10. This rotation of the lever 350 during the forward stroke has no effect on its associated mechanism.

During the midportion of the return stroke of a total operation during a charge transaction, the roller 355 engages the projection 356 from the underside, tending to rotate the lever 350 in a counterclockwise direction. However, the lever 350 is in engagement with a stud 361 mounted on the side printer frame, whereby counterclockwise rotation is prevented. As a result, the arm 311 is rotated clockwise about the shaft 313, the lever 350 sliding forwardly over the stud 361, and the roller 323 is disengaged from the latch shoulder 322 to permit the

return of the validate lever 54 and its associated mechanism to the cash position as described above.

During a total cycle of a cash transaction, it will be appreciated that the arm 311 is in its cash position, and the lever 350 is forwardly of the position in FIG. 10 out of the path of the roller 355.

2. Rendering side printer inoperative

Means are also provided for rendering the side printer inoperative. This means includes a pivotal arm 360 (FIG. 12) carried on a rotatable shaft 362 and having a manually operable knob 364. A crank arm 366 is secured to the rotatable shaft 362 and is connected to a rocker arm 368 (FIGS. 9 and 10) by means of a slide 370. The knob 364 is shown in FIGS. 9 and 12 in the position in which it renders the side printer operative. When the knob is raised, it pivots the arm 360 counterclockwise, moving the slide 370 toward the right to rotate the rocker arm 368 counterclockwise. When the rocker arm is rotated counterclockwise, a slot 372 in the horizontal arm portion thereof receives a stud 374 on the member 296 and rotates the member 296 to a central position in which the pressure rollers 292 and 294 are both spaced from the tape advance roller 298, whereby movement of the tape advance roller will not advance the tape. When the knob 364 is moved to its lowermost position, it causes clockwise rotation of the rocker arm 368, whereby the stud 374 is released by the slot 372, and the member 296 will be released to the charge or cash position, depending upon the position of the validate lever 54.

3. Printing item, subtotal, and total amounts

FIG. 11 shows the improved means for printing the item amounts and the subtotal and total amounts on the cash receipts and credit tickets. One of the numeral wheels 110 and its associated type sector 402 and an aligner 404 are shown disposed above a platen 406. The aligner 404 does not form a part of this invention and it need merely be stated that it is actuated by the main shaft in a well known manner from the position shown into engagement with gear sectors 407 of the wheels 110 at the proper time during the machine cycle.

The platen is mounted for vertical reciprocable movement between slots 409 in upper and lower plates 408 and 410 of a frame 412, and a light spring 414 urges the platen downwardly. The axis of the shaft 123 which supports the wheels 110, the platen 406, and the bar 416 of the aligner are in vertical alignment, whereby the aligner bar in its position engaging the wheels 110 acts as a backstop when the platen is directed against the lower surface of the wheels to print item and total amounts.

A platen firing arm 420 is pivotally mounted on the shaft 313, and a heavy power spring 424, which is connected to the lower arm 426 of the firing arm and to the frame of the cash register urges the firing arm in a clockwise direction (FIG. 11). An upper irregularly shaped projection 428 on the firing arm is normally disposed below a horizontal projection 430 at the upper end of the platen and is received within a slot 431 in the vertical leg 432 of the platen. The spring 414 maintains the upper end of the slot 431 against the upper surface of the projection 428.

The firing of the platen 406 by its firing arm is controlled during each machine cycle by the main shaft 359. During the forward stroke of the machine, the main shaft 359 rotates in a counterclockwise direction (FIG. 11) approximately 98° 50'. A crank arm 434 secured to the main shaft for pivotal movement therewith carries a roller 436 at the outer end thereof. A crank arm 438 mounted for pivotal movement on a shaft 440 has a U-shaped slot 442 at the upper end thereof which receives the roller 436. A pair of spaced crank arms 444 are pinned to the shaft 440 for rotation with the shaft

and the crank arm 433. An elongated latch 446 is carried by a pin 448 received through apertures in the upper ends of the crank arms 444 and is shifted in a generally horizontal plane during rotation of the crank arms 444. The latch includes a shoulder 450 which is engageable with a roller 452 carried on the projection 426 of the platen firing arm. A spring 453 normally maintains the latch 446 against the roller 452.

A second crank arm 454 having a hub portion 461 is carried by the main shaft 359 and includes a slot 455 which receives a roller 457. The roller is mounted for movement with the main shaft, as will be described with respect to FIG. 12, and rotates the crank arm 454 about the main shaft axis. A spring 459 received on the main shaft between crank arms 454 and 357 (FIG. 10) urges the arm 454 into tight frictional engagement with a crank arm 537 (FIG. 12) secured to the main shaft. The crank arm 454 carries a roller 456 which is engageable with a hooklike upper portion 458 of a platen pawl 460 immediately before the end of the forward stroke to raise the pawl 460. The pawl has a vertical slot 463 for pivotal and reciprocal mounting on a shaft 468, and is biased in a counterclockwise direction (FIG. 11) and to its lowermost position by means of a spring 466. A slide 462, which is movable vertically on spaced shafts 468 and 470, will be described in detail with respect to FIG. 12. A roller 472 carried by the pawl is engageable with the latch 446, in the event that the pawl is raised as described above, to rotate the latch counterclockwise (FIG. 11) to release the firing arm 420.

As indicated earlier, the mechanism shown in FIG. 11 normally will be actuated during each machine cycle to drive the platen against the opposed surface of the type sector 402 to print on the receipt or ticket the amount, if any, which has been entered into the cash register. However, when it is desired to render the side printer mechanism inoperable, the manually operable knob 364 is raised to rotate the pivoted arm 360, and a stud 476 carried by the arm engages a projection 478 on the pawl 460 to rotate the pawl clockwise out of the path of the roller 456, whereby the latch 446 will not release the firing arm 420. A spring biased detent 480 and a pin 482 on the arm 360 retain the arm securely in either of its operating positions.

The normal operation of the amount printing mechanism will now be described in detail.

During the initial part of the forward stroke, the type wheels 110 and their type sectors 402 will be rotated to positions determined by the actuation of the numeral keys 42 as described with respect to FIG. 3. The aligner 404 will be rotated counterclockwise into engagement with the gear sectors 409 on the type wheels. Rotation of the main shaft 359 will shift the latch 446 toward the right (FIG. 11), with the right-most end of the latch moving over the roller 472 and the latching shoulder 450 engaging the roller 452 to rotate the firing arm 420 counterclockwise against the force of the power spring 424. Shortly prior to the end of the forward stroke, the roller 456 will engage the hook portion 458 of the pawl 460 and raise the pawl, whereby the roller 472 will engage the latch to rotate it counterclockwise against the force of the spring 453, releasing the firing arm 420. The force of the power spring 424 will move the arm clockwise very rapidly until a projection 484 thereon strikes a suitable stop 485. The platen is moved upwardly at a high velocity by the arm 420 and will continue its upward movement under the force of its own momentum to strike the lower end of the type sector 402 with a substantial impact at a position diametrically opposite the aligner bar 416. It will be appreciated that the cash receipt or credit ticket upon which the amount is to be printed, and the inked ribbon, are interposed between the platen 406 and the lower portion of the type wheels 110 for printing of the amount on the receipt or tape.

The spring 414 will return the platen to its normal

position on the projection 428. During the return stroke, the main shaft restores the crank arms 434, 454, 438, and 444, and the latch 446 to their initial positions. In this regard it will be noted that the roller 457 provides a positive drive for the crank arm 454 and its roller 456 to raise the pawl 460 and that the frictional engagement between the crank arm 537 and the hub 461 returns the crank arm 454 to its initial position during the return stroke.

4. Printing the heading on tape

FIG. 12 illustrates the mechanism for printing the heading for the receipts on cash transactions. It will be recalled that this heading may appropriately contain the name of the store, the date of the transaction, and the number of the transaction. The name of the store may be appropriately recorded on the lower portion of a plate 500, and the number of the transaction and the date may be set on the type sectors of type wheels 502. The date is set by manual control knobs on the side of the upper housing 289 (FIG. 9), which do not form a part of this invention. The means for setting the number of the transaction will be described in detail with respect to FIG. 21.

A single platen 504 (FIGS. 11 and 12) is provided for printing all of the heading information on the plate 500 and on the type sectors 502, and this platen is received in slots 505 in the frame 412 in a manner generally similar to that of the platen 406. The platen is urged downwardly by a light bias spring 506 (FIG. 11) and includes a slot 507 for receiving a firing arm 508. The arm 508 is biased in a clockwise direction by a power spring 510 which is suitably anchored to the machine frame and to the lower projection 512 of the arm 508 by a stud 514.

In the normal at rest condition of the machine, the power spring 510 maintains a lower horizontal lug 516 of the drive arm 503 against the stop 485.

A latch 518 is pivotally connected to the firing arm 508 by a stud 520, and a spring 522 connected between studs 524 and 525 on the drive arm and latch normally maintains a hooklike shoulder 526 in latching engagement with the pin 448 carried by the crank arms 444.

A pawl 528 is pivotally carried on a stud 530 which is secured to the slide 462, and a roller 532 is carried by the stud. The upper end of the pawl 528 includes a shoulder 534 which is engageable during the return stroke of the crank arm 537 by a roller 536 carried thereby in the event that a new heading is to be printed on the cash receipt tape 286, i.e., during the return stroke of the total operation on a cash transaction. The roller 457 which actuates the crank arm 454 (FIG. 11) is secured to the crank arm 537 by means of a stud 539.

The pawl 528 includes a first projection 538 which is engageable by the pin 476. In the event the manually operable arm 360 is rotated counterclockwise to render the side printer ineffective, the pawl 528 is rotated clockwise out of engagement with the roller 536 to render the heading print mechanism inoperable. A second projection 540 on the pawl carries a roller 542 which is engageable by a rocker arm 544 during the return stroke of nontotal cycles of operation of the machine for rotating the pawl 528 out of the path of the roller 536.

The position of the rocker arm 544 is determined by the position of the item accumulator. The item accumulator includes a pair of spaced support arms, the right one of which is shown at 541. The support arms are pivotal about the axis of a pair of studs, one of which is shown at 543, these studs corresponding to studs 284 and 285 shown in FIG. 9 of the Mehan patent No. 2,550,581. The support arms carry an item accumulator frame (not shown) which corresponds to the accumulator frame 90 of said patent. The support arms are shown in the out of mesh position of the accumulator frame in FIG. 12, and are movable counterclockwise to an in mesh position.

75

The support arm 541 is secured to a lever 545 by means of a link 547, the lever being pivotally mounted on a stud 549 secured to the accumulator frame (not shown) for parallel movement with the arm 541. A link 570 is pivotally secured to a stud 551 carried by the lever 545 and to a stud 573 carried by a crank arm 576. The crank arm is secured to and positions a two position control shaft 560 in accordance with the position of the item accumulator frame. This control shaft 560 therefore has two angular positions corresponding to the in mesh and out of mesh positions of the item accumulator frame. The control shaft extends across the width of the machine and is suitably journaled on the end frame plates 593 (FIG. 13) and 553 (FIGS. 12 and 15).

The rocker arm 544 is secured to a pivotal shaft 546 and a crank arm 543 is secured to the shaft in spaced relation to the rocker arm. The crank arm 548 is pivotally connected to a link 558 by means of a stud 552, and the link in turn is pivotally connected to a crank arm 554, which is secured to the two position control shaft 560, and this control shaft therefore determines the angular position of the rocker arm 544, and therefore the angular position of the pawl 528. The control shaft 560 and the linkage connecting it to the rocker arm are shown in the out of mesh position of the item accumulator frame. When the item accumulator frame is shifted to the in mesh position, the arm 541 and the lever 545 are rotated in a counterclockwise direction to raise the link 570 and rotate the control shaft 560 clockwise. The control shaft 560 rotates the crank arm 554 to the broken line position indicated at 555, and the shaft 546 and the rocker arm 544 will be rotated counterclockwise to rotate the pawl 528 in a clockwise direction out of the path of the roller 536.

With respect to FIG. 22, it will be seen that the heading print mechanism of the side printer is rendered effective at approximately the 70° position of the return stroke. At this portion of the return stroke, the item accumulator is in the in mesh position for add, subtract, and subtotal operations and is in the out of mesh position for the total operations.

It has been seen above that the heading print mechanism is rendered inoperative when the item accumulator is in the mesh position, whereby the heading can be printed only during total operations. It will be recalled, however, that there is no need for printing the heading on charge tickets. Means must therefore be provided to render the heading print mechanism inoperative during the total operations of charge transactions.

This means includes a link 556 (FIGS. 10 and 17) which is adapted for movement with the crank arm 318, as will be described later with respect to the detailed description of FIG. 17. The other end of the link is pivotally connected to a crank arm 557 which is secured to an elongated pivotal shaft 558. The shaft carries a lever 559 which engages the roller 542 on the pawl 528. When the validate lever 54 is manually moved to the charge position of FIG. 10 for a charge transaction, the slide 312 rotates the crank arm 318 counterclockwise. The crank arm moves the link 556 toward the left (FIG. 10) to rotate the crank arm 557 and the lever 559 counterclockwise, the lever 559 rotating the pawl 528 out of the path of the roller 536 (FIG. 12). During a subsequent total operation, the heading print mechanism will be ineffective.

The operation of the heading print mechanism during a total operation of a cash transaction will now be described in detail.

During the initial portion of the forward stroke, the main shaft 359 rotates the crank arms 438 and 444 clockwise (FIG. 12) by means of the crank arm 434 and roller 436 as described above with respect to the amount printer mechanism. The pin 448 urges the latch 518 toward the right, the latch moving under the roller 532 and also rotating the firing arm 508 counterclockwise. As the main shaft approaches the end of the forward stroke, the roller 536 rotates the pawl 528 slightly clockwise and positions

itself above the shoulder 534 of the pawl. During the initial portion of the return stroke, the roller 536 moves the pawl 528 and the slide 462 downwardly.

At about the 70° position during the return stroke, the roller 532 carried by the slide disengages the shoulder 526 of the latch 518 from the pin 448. The firing arm 508 is released and rotated clockwise at a high velocity by the power spring 510. The firing arm drives the platen upwardly toward the plate 500 and the type sectors 502 at a high velocity. The ear 513 at the lower end of the firing arm engages the stop 485 to terminate the firing arm's movement. However, the momentum of the platen carries it upwardly into engagement with the plate and type sectors to print the heading on the cash receipt.

15 A spring 572 secured to the roller 542 and to the side printer frame returns the pawl 528 and the slide 462 to their initial upper positions. The crank arm 434 on the main shaft returns the crank arms 438 and 444 to their initial positions and resets the latch 518.

20 5. Validate lever release

The mechanism for automatically releasing the validate lever 54 and its associated latching means during the return stroke of a total operation while the validate lever is 25 in the charge position, will now be described.

When the validate lever 54 is moved from the cash to the charge position of FIG. 10 for a charge transaction, the crank arm 318 and the latch 321 are rotated in a counterclockwise direction to the position of FIG. 10, in 30 which the roller 323 carried by the rocker arm 311 is urged downwardly into latching engagement with the shoulder 322 on the latch, and the projection 356 on the lever 350 is moved rearwardly to the position of FIG. 10 in the path of the roller 355. The slide 354 is allowed 35 to move rearwardly, pulled by spring 575 (FIG. 12) to the position of FIG. 10. The slide includes a slot 571 (FIG. 12) which receives a stud 573 connected to the rocker arm 544. The spring 575 is secured to the stud 573 and also to a stud 577 on the slide and biases the latter rightwardly 40 (FIG. 12).

During the return stroke of add, subtract, and subtotal operations, the item accumulator is in the in mesh position whereby the rocker arm 544 is rotated to a counterclockwise position from that shown in FIG. 12. This moves the stud 573 into engagement with the left shoulder 45 of the slot 571 and shifts the slide 354 forwardly to rotate the lever 350 clockwise to move the projection 356 out of the path of the roller 355, thereby preventing the release of the validate lever mechanism.

During the initial portion of the return stroke of a total 50 operation on a charge transaction, the item accumulator is moved to the out of mesh position, and the rocker arm 544 is rotated to the position of FIG. 10. The slide 354 is moved rearwardly to the position of FIGS. 10 and 12 to rotate the lever 350 counterclockwise to the position 55 shown in FIG. 10. Shortly thereafter, the roller 355 engages the projection 356 of lever 350. Since the stud 361 prevents counterclockwise rotation of the lever 350, the rocker arm 311 is moved clockwise by the roller 355 and the lever 350 to release the latch 321 for return of 60 the validate lever mechanism to the cash position as described above with respect to FIG. 10.

IV. CASH REGISTER DRAWER RELEASE

The accumulator control shaft 560 also controls the 65 release of the usual cash register drawer (not shown) just prior to the end of the return stroke of the machine for total operations and certain nonadd cycles such as paid out, nonsale, and the like. This mechanism is shown in detail in FIGS. 13 and 14 and includes the item accumulator control shaft 560 and a crank arm 582 which is secured to the control shaft. The crank arm 582 is pivotally secured to a slide 584 by a stud 586 and the slide includes an elongated lost motion slot 588 which receives 70 a stud 590 therethrough.

The stud 590 is secured to the lower end of a pawl 592, and the pawl is supported on an arm 594 by means of a stud 596 for limited pivotal movement determined by the stud 590 and the slot 588. A spring 597 biases the pawl in the clockwise direction. The arm 594 is pivotally supported on a frame plate 598 by means of a stud 600. A rocker arm 602 is pivotally supported on the frame plate 598 by means of a stud 604, and a roller 606 carried at one end of the rocker arm coacts with a hooklike portion 608 of the pawl 592 for releasing the cash drawer to its open position during the total and nonadd cycles. A roller 610 carried at the other end of the rocker arm 602 is maintained in engagement with a cam 612 carried by and rotated with the main shaft 359 by means of a spring 614.

A link 616 pivotally secured to the arm 594 by means of a stud 717 is connected at its lower end to a crank arm 618 by means of a stud 620. The crank arm 618 is connected to a pivotal shaft 622, and a latch 624 is secured to the shaft 622 in spaced relation with the crank arm. The latch includes a hooklike portion 626 which cooperates with a pin 628 to maintain the cash drawer (not shown) in its closed position. An arm 630 secured to the cash drawer supports a bracket 632 which carries the pin 628, and a strong spring 634 is secured to either side of the housing (not shown) around the cash drawer by means of studs 636 and is received around a depending projection 638 carried by the arm 630 to bias the drawer toward the open position.

A description of the operation of the cash drawer opening mechanism will now be made. During the forward stroke of the main shaft 359, the cam 612 will be rotated clockwise, permitting the spring 614 to rotate the rocker arm 602 in a counterclockwise direction, the roller 606 carried by the rocker arm moving the pawl 592 out of the way and assuming a position below its hooklike portion 608. During the return stroke of the machine, the cam 612 will rotate the rocker arm 602 in a clockwise direction, and in the event that the roller 606 engages the hooklike portion of the pawl, the pawl 592 will be raised to rotate the arm 594 in a clockwise direction about the axis of the stud 600. When the arm 594 is rotated in a clockwise direction, the link 616 is raised to rotate the crank 618, the shaft 622, and the latch 624 in a counterclockwise direction to release the pin 628. The arm 630 and the cash drawer to which it is attached will be moved in a cash drawer opening direction toward the right (FIG. 13) by the spring 634.

A stud 640 secured to the frame plate 598 engages a projection 642 on the pawl 592 to limit the upward movement of the pawl by the rocker arm 602. Rotation of the rocker arm 602 after the projection 642 engages the stud 640 causes counterclockwise pivotal movement of the pawl about the stud 640, whereby the hooklike portion 608 of the pawl is disengaged from the roller 606 and a spring 644 returns the pawl and arm 594 to their initial positions.

The release of the cash drawer near the end of the return stroke is therefore dependent upon the position of the pawl 592 at this time. As indicated earlier, the pawl will be in the position shown in the event that the operation is a total or nonadd, because the control shaft is in the out of mesh position shown in FIG. 13. However, during the return stroke of an add, subtract, or a subtotal operation, the accumulator control shaft 560 will have been rotated counterclockwise to its in mesh position to rotate the crank arm 582 in a counterclockwise direction. The crank 582 will move the slide 584 toward the right with respect to FIG. 13 to rotate the pawl 592 in a counterclockwise direction so that its hooklike portion 608 is out of the path of the roller 606 when the rocker arm 602 is rotated in the clockwise direction during the return stroke. Thus, with the pawl in its counterclockwise position, the cash drawer will not be opened.

V. TAPE AND CHARGE RECEIPT ADVANCE OPERATION

The tape advance mechanism of FIGS. 15-20, inclusive, will now be described.

FIG. 15 shows this mechanism from the left side conditioned for a cash transaction prior to the initiation of a cycle of operation of the cash register. FIG. 17 shows the mechanism from the right side conditioned for a charge transaction during the first part of the return stroke. The tape advance mechanism comprises a jump feed gear 650 (FIG. 15) which is carried by the main shaft 359 for free rotatable movement thereon. The gear 650 meshes with a single feed gear 654 which is freely rotatable on a shaft 656. The gear 654 meshes with a pinion 658 which is carried on a hub 660 which freely rotates on shaft 652 (FIG. 17). An idler pinion 666 secured to the hub 660 rotates with the pinion 658 and meshes with a pinion 668. The pinion 668 has a hub 670 which is secured to the tape feed roller 290.

A feed pawl 672 cooperates with the gear 654 for advancing the tape one space for each nontotal cycle of machine operation during a cash transaction.

A feed pawl 674 cooperates with gear 654 during each cycle of machine operation during a charge transaction to advance the charge receipt one space. The pawl 672 is pivotally connected to an arm 676 by a stud 680, and the pawl 674 is pivotally connected to a pair of arms 677 and 678 on opposite sides of gear 654 by a stud 682. The arms 676, 677, and 678 are freely pivotal on the shaft 656. A pair of springs such as spring 686 are secured to the respective pawls and their associated arms for biasing the pawls toward the gear 654. Studs 688 and 690, carried respectively by the pawls 672 and 674, engage a plate cam 692 when the arms carrying the pawls are rotated in clockwise and counterclockwise directions respectively (FIG. 15). The plate cam is freely rotatable on the shaft 656 and is selectively positioned, as will be described later, for rendering either one of the pawls ineffective to drive the gear 654, depending upon the type of transaction and the type of machine operation.

A jump feed pawl 694 is pivotally carried by a pair of arms 696 and 697 which are freely pivotal on the main shaft 359. The jump feed pawl 694 is rendered effective to drive the gear 650 only during a total operation of the machine during a cash transaction to advance the cash receipt tape nine spaces. The arm 697 also carries a pivotal latch 698 which has a pair of semi-circular recesses 700 for receiving a stud 702 carried by the jump feed pawl to latch the pawl in either of two positions in or out of mesh with the gear 650. A spring 704 connected to studs 706 and 708 on the jump feed pawl and the pivotal latch respectively, biases the stud 702 of the pawl toward the latching recesses 700.

A drive cam 710 having a hub portion 712 is secured to the main shaft 359 for rotation therewith. The cam carries a stud 714. A pair of springs 716 and 718 are connected to the stud 714 and to studs 720 and 722, which are carried respectively by the pawl supporting arms 676 and 678. During the forward stroke of the machine the cam plate 710 is rotated clockwise (FIG. 15) and the springs 716 and 718 provide a driving connection between the cam 710 and the pawl supporting plates to rotate the plates 676, 677, and 678 respectively in clockwise and counterclockwise directions. A link 724 is carried by the stud 720 and includes a lost motion slot 726 through which the stud 714 is received. The elongated slot 726 permits movement of the stud 714 relative to the link 724 when the cam plate 710 completes the final portion of the forward stroke movement. During the return stroke of the cam plate, the stud 714 and the right shoulder of the slot 726 provide a positive drive connection between the cam plate and the pawl arm 676 to assure rotation of the gear 654 by the pawl 672 in

the event the pawl is to advance the gear one position for single spacing of the receipt tape during a cash transaction.

Similarly, a link 730 having a slot 732 is secured to the cam plate 710 by a stud 734 and to the pawl supporting arm 678 by a stud 736. The link 730 thus provides a positive drive action between the cam plate and the pawl supporting arm 678 to assure rotation of gear 654 during each machine cycle during a charge transaction. A link 738 is secured to the pawl carrying arm 678 by the stud 722 and includes a slot (not shown) through which is received a stud 740 carried by the arm 696 which carries the jump feed pawl. Rotation of the pawl carrying arm 678 in the counterclockwise direction will cause similar counterclockwise rotation of the pawl carrying arms 696 and 697 by means of the link 738.

The cam plate 710 also actuates a safety mechanism for preventing the manual operation of the validate lever 54 from one position to the other during certain portions of a machine cycle to prevent jamming of the tape advance mechanism. This safety mechanism comprises a cam follower 750 having a hub 754 which is pivoted on a stud 752. A latch 756 is secured to the other end of the hub for pivotal movement of the latch with the cam follower. A spring 758 secured to a hooklike portion 760 of the latch and to a stud 762 secured to the end frame plate 553 biases the latch in a clockwise position in spaced relation from a pivotal arm 764 which includes a notch 766 with which the latch 756 coacts to prevent movement of the validate lever arm. The arm 764 is secured to the shaft 320 for pivotal movement with the shaft and the crank arm 318 (FIG. 10) when the validate lever arm 54 is actuated from one position to the other. The arm carries a stud 770 which is received through and cooperates with a slot 772 in the end frame plate 553 for limiting the pivotal movement of the arm.

The upper end of the arm 764 is pivotally secured to the link 556 which together with crank arm 557, shaft 558, and lever 559 (FIG. 10) controls the heading print mechanism as described above. The crank arm 557 carries a roller 782, the purpose of which will be described below. The arms 764 and 557 and the link 556 are shown in the positions they assume when the validate lever is in the cash position of FIG. 15, and FIG. 17 shows these components in the positions they assume when the validate lever is in the charge position.

When the validate lever arm 54 is in the charge position, the arm 764 is rotated clockwise (FIG. 15). However, in the cash position of the validate lever arm, the arm 764 is in the position shown in FIG. 15 where it cooperates with the latch 756 during at least a portion of the machine cycle to prevent inadvertent manual shifting of the validate lever to the charge position. The shape of the cam plate 710 in such that the latch 756 momentarily engages the notch 766 in the arm 764 at the beginning of the forward stroke, and then again toward the end of the forward stroke. Also, the latch momentarily engages the notch during the beginning of the return stroke and for a very short duration just before the end of the return stroke. However, it releases the arm 764 at the end of the return stroke. It has been found sufficient to render the latch effective at these particular portions of the machine stroke so that jamming of the mechanism, which might otherwise occur, is avoided.

The control of the tape advance mechanism for either single spacing or jump spacing is determined by the position of the accumulator frame control shaft 560 as well as the position of the validate lever 54 during the return stroke. As best seen in FIGS. 19 and 20, a jump feed control arm assembly 790 comprise a crank arm 792 secured to the control shaft 560 for rotation therewith and an extension 794 secured to the crank arm by means of a screw 796 and a stud 798. A jump feed pawl trip arm 800 is freely pivotal on the shaft 558 and is biased

toward the jump feed control arm assembly 790 by means of a bias spring 802 secured to studs 804 and 806 on the control arm assembly and the feed pawl trip arm. The upper end of the trip arm carries a roller 808 which bears against the adjacent edge of the extension 794 of the control arm.

1. Tape advance during add cycle on cash transaction

During an add cycle on a cash transaction, the control shaft 560 maintains the jump feed control assembly 790 in the position shown in FIG. 15 during the forward stroke, and the pawl 694 is rotated by the main shaft 359 and arms 696 and 697 to the position shown in FIG. 16. The cam plate 710 rotates the pawls 672 and 674 to the positions shown in FIG. 17. During the initial portion of the return stroke, the control shaft rotates the jump feed assembly 790 counterclockwise, the assembly engaging the roller 808 on the trip arm 800 to force the roller against the pawl 694 as shown in FIG. 16, to maintain the pawl disengaged from the gear 650. The cam plate 692 for the add pawls 672 and 674 will be in the position shown in FIG. 15, and as the machine approaches the end of the return stroke, the stud 688 will leave the cam plate 692 to permit the spring 686 to engage the pawl 672 with the teeth on the gear 654 to permit advancement of the cash receipt tape one space.

2. Tape advance during total cycle on cash transaction

During a total cycle of operation on a cash transaction, the item accumulator will be moved to its in mesh position during the initial part of the forward stroke, and the control shaft 560 will rotate the feed control arm assembly 790 in a counterclockwise direction, the assembly engaging the roller 808 to move the trip arm 800 to the position shown in FIG. 16. The pawl 694 is moved to the position shown in FIG. 16 at the end of the forward stroke. Shortly after the beginning of the return stroke, the item accumulator will be moved to its out of mesh position, and the control shaft 560 will rotate the jump feed control assembly 790 in a clockwise direction (FIG. 16) and the spring 802 will urge the trip arm 800 in a counterclockwise direction. The trip arm will engage the outer end of the latch 698 to lift the latch sufficiently to permit the spring 704 to rotate the pawl 694 into engagement with the teeth of the gear 650, and the stud 702 on the pawl will be moved to the outermost slot 700 in the latch where it is maintained. As the return stroke continues, arms 696 and 697 are rotated in a clockwise direction (FIG. 15) carrying the pawl 694 with them to rotate the gear 650 in a clockwise direction for a jump feed advancement of the cash receipt tape.

3. Charge receipt advance

For each charge transaction, the validate lever arm 54 is moved to its rear position to rotate the shaft 320 and the arm 764 counterclockwise (FIG. 17). The link 556 rotates the crank arm 557 counterclockwise, and the roller 782 rotates the trip arm 800 to the position shown in FIG. 17. The trip arm is retained in this position at all times during the charge transaction whereby the pawl 694 cannot be released for meshing engagement with the gear 650. Thus, during a charge transaction, the jump feed control is rendered inoperative.

A stud 809 (FIG. 17) secured to the arm 764 is received through a slot 811 in the cam plate 692. When the validate lever is moved to its rearmost charge position, the arm 764 is rotated counterclockwise (FIG. 17) to move the cam plate 692 from the cash position of FIG. 15 to the charge position of FIG. 17. With the cam plate 692 in a position shown in FIG. 17, the pawl 672 is rendered inoperative during an add cycle and the pawl 674 is rendered operative during the add cycle to rotate the gear 654 in a clockwise direction at the end of the return stroke to rotate the receipt advance roller 290 in a counterclockwise direction (FIG. 9) for proper ad-

vancement of a receipt between the roller 290 and the roller 294.

VI. CONSECUTIVE NUMBERING DEVICE

A consecutive numbering device 819 (FIGS. 11, 12, 17, and 21) is provided for printing the number of each cash transaction on the cash receipt. The numbering device includes a type wheel 822 coaxial with the type wheels 502 for each denomination, each wheel being secured to a ratchet 826. The type wheels and ratchets are rotatably carried by a stationary shaft 832 mounted on the end frame plate 553 and the upper side printer housing 280. Each ratchet 826 is engageable on a feed finger 828 on an arm 830 pivotally supported by a shaft 834. A generally U-shaped crank arm 836 is pivotally carried by the shaft 832 and is secured to the shaft 834 to permit movement of the shaft 834 in a generally vertical arcuate path about the axis of the shaft 832. A spring 838 secured to a lug 839 on the arm 830 and to the crank arm 836 biases the feed fingers 828 toward the ratchets 826. A plurality of detents 840 are provided for the ratchets and are biased toward engagement with the ratchets by springs 842 which are secured to the detents and to a shaft 844.

The shaft 834 is received through a slot 846 in a drive crank 848 which is pivotally carried on an eccentric pivot stud 850 secured to the end frame plate 553. The drive crank carries a stud 852 which is received through an elongated slot 854 in a drive link 856. The drive link is secured by a stud 858 to the drive arm 697 of the jump feed mechanism.

The stud 852 is also received through an aperture 860 in one end of a latch 862. A slide 863 is secured to the other end of the latch by means of a stud 864. A spring 866 is secured to a stud 867 on the slide and to a stud 868 secured to the end frame plate 553 to urge the slide and latch downwardly. The stud 868 is received through a slot 870 in the slide to permit vertical movement of the slide.

The latch 862 has a shoulder 872 which engages a stud 874 carried by the end frame plate 553, and while the stud is engaged by the shoulder, the clockwise pivotal movement of the drive crank 848 is prevented.

The mechanism for actuating the numbering device will now be described. It will be recalled that the firing arm 508 (FIG. 12) for the heading print mechanism is released to drive its associated platen 504 into engagement with the associated type wheels 502 and bar 500 during total cycles of machine operation for cash transactions only. This heading print mechanism is also utilized to advance the consecutive numbering device. A bail 880 is pivotally mounted on the shaft 313 which carries the firing arm 508 and the bail comprises a first downwardly extending arm 882 which carries a stud 884 which is engageable with the lower projection 512 on the firing arm 508. The bail also includes a second generally upwardly extending arm 886 spaced from the arm 882 and carrying a firing stud 888 adjacent the outer end thereof. The stud 888 is received through a slot 889 (FIG. 12) in the end frame plate 553. A light spring 890 connected to the pin 884 on the bail and to the stud 524 on the firing arm 508 biases the stud 884 toward the firing arm.

When the firing arm 508 is released the return stroke of a total operation on a cash transaction, as described above (FIG. 12) for rapid clockwise movement to drive its associated platen, the bail 880 is carried with the firing arm in a clockwise direction. When the firing arm strikes the stop 485, the momentum of the bail carries it further in a clockwise direction against the force of the light spring 890. There is sufficient energy stored in the bail at this time for the firing pin 888 carried by the bail to strike the latch 862 and disengage the shoulder 872 thereof from the stud 874. The latch is moved toward the left (FIG. 21) by means of the heavy bias spring 851 which now rotates the drive crank 848 in a clockwise direction about the pivot stud 850.

The drive crank moves the shaft 834 downwardly in an arcuate path about the axis of the shaft 832, and the units finger 828 rides over the surface of its ratchet to position itself in the next drive shoulder of the ratchet.

The consecutive numbering device is now in a position for advancing the ratchet 826 associated with the units denomination for advancement of the numbering device one position. During this time the drive link 856 is moved toward the right by the pawl drive arm 697 and the left shoulder of the slot 854 in the drive link engages the stud 852 to rotate the drive crank 848 in a counterclockwise direction which moves the shaft 834 upwardly in an arcuate path. This movement of the shaft 834 causes the feed finger associated with the units denomination ratchet to rotate the ratchet one position. At the same time, the latch 862 is moved toward the right until the shoulder 872 again engages the stud 874.

One of the drive shoulder configurations indicated at 827 on each ratchet is more deeply recessed than the others. This permits the tens, hundreds, and thousands denominations fingers to engage a drive shoulder on their respective ratchets 826 to advance the ratchets when the next lower denomination ratchet advances its type wheel from the "9" to the "0" position.

While there has been shown and described a preferred embodiment of the invention, it will be apparent that numerous modifications and variations thereof may be made without departing from the underlying principles of the invention. It is intended, therefore, by the following claims to include within the scope of the invention all such variations and modifications by which substantially the results of the invention may be obtained through the use of substantially the same or equivalent means.

The invention claimed is:

1. In a cash register adapted to perform add and total operations for cash and charge transactions and having a side printer for issuing cash receipts from a tape and for issuing individual charge receipts, means for advancing the cash and charge receipts, a consecutive numbering device, form print means for printing a heading on the cash receipts and for actuating the numbering device, a cash drawer latching mechanism, an item accumulator control shaft selectively operated in one manner during each add operation and in another manner during each total operation, a manually operable validate lever having cash and charge positions, control mechanisms selectively operated by the control shaft and the validate lever rendering the advancing means effective for each cash transaction to advance the cash receipt tape a first desired amount and a second greater desired amount during each add and total operation respectively and for each charge transaction to advance a charge receipt a desired amount during each add and total operation, control mechanisms selectively operated by the control shaft and the validate lever rendering the form print means effective only during each total operation of a cash transaction, and means selectively operated by the control shaft rendering the latching mechanism ineffective only during total operations.

2. The combination claimed in claim 1 including manually operated means rendering the side printer ineffective.

3. In a cash register adapted to perform add and total operations and having a side printer for issuing cash receipts from a tape and for issuing individual charge receipts, the combination comprising a control shaft selectively operated in one manner during each add operation and in another manner during each total operation; a manually operated validate lever having cash and charge positions and an intermediate inoperative position; first and second advancing means adapted to receive and advance cash and charge receipts respectively; means operated by the validate lever rendering the first and second advancing means effective in the cash and charge positions of the lever respectively; means controlled by the control shaft and the validate lever in the cash position of the

validate lever operating the first advancing means for a desired degree of advancement of the cash receipt tape during each add operation and for a desired greater degree of advancement of the tape during each total operation and in the charge position of the validate lever operating the second advancing means for a desired degree of advancement of a charge receipt during each operation; and manually operated means connected to the first and second advancing means to render them ineffective and to latch the validate lever in the intermediate inoperative position.

4. In a cash register adapted to perform add and total operations and having a side printer for issuing cash receipts from a tape and for issuing individual charge receipts, the combination comprising an item accumulator control shaft selectively operated in one manner during each add operation and in another manner during each total operation; a main shaft; a manually operated validate lever having cash and charge positions; and a cash tape and charge receipt advancing mechanism including first and second advancing means adapted to receive and advance cash tape and charge receipts respectively, drive means connected for actuation by the main shaft during each operation, a mechanism connecting the drive means to the first and second advancing means, means operated by the validate lever rendering the first and second advancing means effective in the cash and charge positions of the lever respectively, and means operated by the control shaft and the validate lever to condition the drive means in the cash position of the validate lever for a desired degree of advancement of the cash receipt tape during each add operation and for a desired greater degree of advancement of the tape during each total operation and in the charge position of the validate lever to condition the drive means for a desired degree of advancement of a charge receipt during each operation.

5. In a cash register adapted to perform add and total operations and having a side printer for issuing cash receipts from a tape and for issuing individual charge receipts, the combination comprising an item accumulator control shaft selectively operated in one manner during each add operation and in another manner during each

total operation; a main shaft; a manually operated validate lever having cash and charge positions; and a cash tape and charge receipt advancing mechanism including a drive roller and a first idler roller and the drive roller and a second idler roller adapted to receive and advance cash tape and charge receipts respectively, drive means connected for actuation by the main shaft during each operation, a gear train connecting the drive means to the drive roller, means operated by the validate lever rendering the drive roller and first idler roller and the drive roller and second idler roller effective in the cash and charge positions of the lever respectively, and means operated by the control shaft and the validate lever to condition the drive means in the cash position of the validate lever for a desired advancement of the gear train during each add operation and for a desired greater degree of advancement of the gear train during each total operation and in the charge position of the validate lever to condition the drive means for a desired degree of advancement of the gear train during each operation.

6. The combination claimed in claim 5, including manually operated means for holding both said idler rollers ineffective to advance either the cash tape or the charge receipt.
